UNITED STATES PATENT OFFICE.

ELLSWORTH E. FLORA, OF CHICAGO, ILLINOIS, ASSIGNOR TO ZORGE SAFETY RAILWAY EQUIPMENT COMPANY, OF CHICAGO, ILLINOIS.

ALARM-SIGNAL.

No. 853,579.

Specification of Letters Patent.

Patented May 14, 1907.

Application filed March 8, 1906. Serial No. 304,918.

To all whom it may concern:

Be it known that I, ELLSWORTH E. FLORA, a citizen of the United States, residing at Chicago, in the county of Cook and State of Illinois, have invented a new and useful Improvement in Alarm-Signals, of which the following is a specification.

My invention relates particularly to means for giving warning to an engineer, or motor-man, approaching an open switch, or an open draw, with his train, or car; and my primary object is to provide improved apparatus involving the use of a device which will be preparatorily set when the switch is thrown open, and which will operate to detonate a torpedo, or explosive body, when a train passes over in approaching the switch.

The invention constitutes an improvement upon the alarm signal disclosed in the application of Robert J. Zorge, Serial No. 303,487 filed in the United States Patent Office on the 5th day of February, 1906.

The invention is illustrated in the accompanying drawings, in which—

Figure 1 represents a diagrammatic view of a portion of a railway track equipped with my improved alarm device; Fig. 2, a broken perspective view of a train-actuated switch employed in connection with an electric circuit of the device; Fig. 3, an elevational view of the switch shown in Fig. 2, showing also the relation of the switch to the rail of the track; Fig. 4, a broken plan view showing a fragment of a rail and the mechanism of my alarm device in relation thereto; and Fig. 5, a section taken as indicated at line 5 of Fig. 4 and showing also the relation of a wheel passing over the rail.

In the preferred construction, A represents the main track of a railway; B, a side track; C, a switch-point operated by any convenient means (not shown); and D, my improved device electrically connected with the switch-point said device operating to cause an explosion, or a series of explosions, in the event that a train passes over the track in the direction indicated by the arrow while the switch-point is open.

The device D preferably comprises a casing d having a lower chamber d¹ and an upper chamber d², the chambers being separated by a plate d³ and the upper chamber having a removable top d⁴; a rotary torpedo-carrier d⁵ located in the upper chamber and having

a depending sleeve d⁶ journaled in a bearing 55 in the plate d³ and resting at its lower end on a spring-casing d⁷ which is located in the lower portion of the chamber d¹; a shaft d⁸ extending through the sleeve d⁶ and into the casing d⁷, said shaft being connected by a 60 stud d⁹ with a coil-spring d¹⁰ whose outer end is joined by studs d¹¹ to the casing; a ratchet-wheel d¹² fixed on the upper end of the shaft d⁸; a pair of spring-held pawls d¹³ mounted on the carrier d⁵ and engaging the ratchet-wheel 65 d¹²; a locking lever d¹⁴ whose lower end is supported on a pivot d¹⁵ and whose upper end projects through a slot d¹⁶ in the plate d³, said locking lever controlling the movement of the carrier d⁵; a magnet d¹⁷ having 70 an armature d¹⁸ controlling the movement of the locking member d¹⁴; an electric circuit d¹⁹ in which is included the winding of the magnet d¹⁷ and a battery d²⁰, said circuit having a conductor d²¹ leading to a contact point 75 d²² and a conductor d²³ connected with the switch-point C, and said circuit having also conductors d²⁴, d²⁵ connected with a train-actuated switch d²⁶. It is to be borne in mind that the mechanism shown diagrammatically in Fig. 1 is, in practice, properly incased, as shown in Figs. 4 and 5.

The casing d may be of cylindrical form with one side made flat, or segmental, as indicated at g to enable the casing to be placed close to a track-rail. The shaft d⁸ is journaled near the flat side of the casing, and the top d⁴ of the chamber d² is provided with an opening g¹ through which the torpedoes may be projected by the carrier and placed upon 90 the adjacent rail of the track. The top d⁴ is, preferably, pivotally and removably connected with the body of the casing, the details of the connections being unimportant. The carrier d⁵ is shown in the form of a disk 95 equipped with two diametrically opposite sockets g² which serve to receive shanks g³ of torpedoes g⁴. The shanks g³ are provided at their ends with slots g⁵ which receive clamping screws g⁶, whereby the torpedoes are 100 firmly secured in place. The normal position of the torpedoes is shown in Fig. 4, from which it will be understood that the torpedoes lie normally parallel with the track rail and housed in the chamber d². The carrier 105 d⁵ is provided on its lower side with a pair of diametrically opposite locking shoulders g⁷ arranged on a circle of given diameter, and

on a diameter at right angles to the diameter containing the shoulders g^7 and on a larger circle with diametrically opposite locking shoulders g^8 . The locking lever d^{14} is normally held in the position shown in Fig. 5 by the magnet d^{17} , in which position it is in the path of the stops g^8 of the torpedo-carrier. The spring g^9 tends to throw the locking lever d^{14} to the other limit of its movement and thus bring the upper end of the locking lever into the path of the stops g^7 of the torpedo-carrier. When the magnet d^{17} is de-energized, as by the breakage or failure of its circuit, the lever d^{14} will be actuated by the spring g^9 , thereby disengaging the lever from the stop g^8 with which it is in engagement and moving it into the path of the next succeeding stop g^7 , so that the torpedo-carrier will be permitted to make a quarter turn, thereby placing a torpedo above the track-rail at the point indicated at h in Fig. 4. Each stem g^3 is formed with a head having, in the construction shown, three torpedoes mounted thereon so arranged as to be presented longitudinally of the rail when in position for exploding, it being understood that the arrangement is designed to cause a series of explosions in rapid succession when a wheel passes over the torpedoes.

In Fig. 1, I have shown an electric circuit K provided with a bell k and a battery k^1 , said circuit being connected with the torpedo-carrier d^5 and with a contact-point k^2 (see Fig. 5) adapted to make contact with the spring d^{10} when the latter expands in actuating the carrier. The purpose of the circuit K is to give warning when the spring requires rewinding. The bell may be located at a station, if desired, so that an attendant can see that the device is rewound. Ordinarily, it is expected that it will be the duty of the train crew to see that the device is recharged after an alarm signal has been given.

The switch d^{26} of the electric circuit d^{20} is designed to break the circuit at the point where said switch is located when a train passes in the direction indicated by the arrow in Fig. 1. The spring comprises spring contact members l with which the conductor d^{25} is connected; a horizontal switch-lever l^1 supported to turn freely on a pivot l^2 ; and an actuating arm l^3 supported to turn freely on said pivot and connected with the arms of the lever l^1 by springs l^4 , l^5 . A yielding catch l^6 is adapted to engage and hold the lever l^1 after it has been actuated to break the circuit by a train moving in the direction of the arrow indicated in Fig. 1. A train moving in the opposite direction will reset the switch in its closed condition. The conductor d^{24} is in electrical connection with the switch-lever, as shown in Fig. 1.

The operation may be briefly stated: Assuming the switch-point C to be closed, a train may pass over the track in either direc-

tion without affecting the mechanism. Assuming the switch-point C to be open, a train passing over the track in the direction indicated by the arrow in Fig. 1 will operate the switch-lever l^1 , thereby breaking the circuit at that point, so that the magnet d^{17} will be de-energized, permitting the spring g^9 to move the locking lever d^{14} from the position shown in Fig. 5 to the other limit of its movement, where it will be in position to engage the succeeding stop g^7 . The spring d^{10} will now operate to turn the shaft d^8 and the ratchet-wheel d^{12} , which will, through the medium of the pawls d^{13} , turn the torpedo-carrier through an angle of 90° , or until the stop g^7 engages the movable stop d^{14} . The relation of the casing d to the adjacent rail of the track is such that when the torpedo-carrier makes a quarter turn from the position shown in Fig. 4, a torpedo will be placed above the rail in position to be struck by a wheel of a passing train. The manner of supporting the casing d is not shown, but it will be understood that the casing is firmly supported in any suitable manner on the outer side of the adjacent rail, so that the stem of the torpedo will not be engaged by the flange of the wheel. After operation of the device, the torpedo carrier will, upon closure of the circuit d^{20} , either at the switch-point C , or at the electric switch d^{26} , make a quarter revolution, owing to the fact that the vibratory stop d^{14} will be retracted against the action of its spring upon the energization of the magnet d^{17} . This will leave the device in condition for a second operation. As has been indicated, however, train crews will be instructed to recharge and reset the device after each operation; and, where possible, warning will be conveyed by the circuit K to some attendant whose duty it is to keep watch of the detonating device.

It is obvious that many changes in details of construction within the spirit of my invention may be made, so that the foregoing detailed description should be understood as having been given for clearness of understanding only.

The improved device may be usefully employed in connection with switches, draw bridges, visual signals, crossings, and in various other situations.

What I regard as new, and desire to secure by Letters Patent, is—

1. The combination with a track-rail, of a torpedo-carrier operating to place a torpedo immediately above the rail, a spring serving to operate said torpedo-carrier, stops on the torpedo-carrier, a vibrating stop co-acting with both of said first-named stops, a spring serving to move said vibrating stop in one direction, and an electro-magnet serving normally to hold said vibrating stop against the action of its spring.

2. The combination with a railway track,

of a device for the purpose set forth, comprising a rotary torpedo-carrier, a spring tending to rotate said torpedo-carrier, stops arranged on different radii and moving with the torpedo-carrier, and a suitably controlled vibratory stop located to oscillate between and coact with said first-named stops.

3. A device for the purpose set forth, comprising a casing having an upper chamber and a lower chamber, a torpedo-carrier housed in the upper chamber, a shaft extending through the torpedo-carrier and equipped at its lower end with an actuating spring, ratchet-wheel and pawl connection between the upper end of the shaft and the torpedo-carrier, stops carried by the torpedo-carrier, a substantially vertical vibratory stop, a spring tending to move said vibratory stop in one direction, a magnet tending to move said vibratory stop in the other direction, and a circuit for said magnet controlled with relation to the condition of a railway track.

4. The combination with a railway track

having a movable switch-point, of a torpedo-carrier, potential means for actuating said carrier, an electro-magnet controlling the movement of the torpedo-carrier, and an electric circuit, or circuits, for said magnet having a make and break device controlled with relation to the movement of the switch-point and having also a train-controlled electric switch, for the purpose set forth.

5. The combination with a railway track having a movable switch-point, of a torpedo-carrier, a magnet controlling said torpedo-carrier, a branch circuit for said magnet connected with the switch-point, and a second branch circuit for said magnet having a train-actuated normally closed switch located on the opposite side of the detonating device to which the switch-point of the railway track is located, for the purpose set forth.

ELLSWORTH E. FLORA.
